Siechenstrasse 8/10, both of Wiedenbruck, Germany

Filed June 20, 1967, Ser. No. 7,531

Term of patent 14 years

(Cl. D14—27)

FIG. 1.

FIG. 2.

FIG. 3

FIG. 1 is a perspective view of an adjustable roof for camping vehicles, in collapsed condition, showing our new design;

FIG. 2 is a perspective view thereof, in extended position; and

FIG. 3 is a front end elevation with a portion of the roof in raised position.

The motor vehicle shown in broken lines is only included for illustrative purposes.

The side opposite that shown in FIGURES 1 and 2 is a mirror image thereof.

We claim:

The ornamental design for an adjustable roof for camping vehicles, as shown and described.
